WILLIAM H. BRADY, OF ROSELLE, NEW JERSEY, ASSIGNOR TO DIEHL MANUFACTURING COMPANY, OF ELIZABETH, NEW JERSEY, A CORPORATION OF NEW JERSEY.

LIGHTING DEVICE FOR SEWING MACHINES.

Application filed January 23, 1922. Serial No. 531,027.

To all whom it may concern:

Be it known that I, WILLIAM H. BRADY, a citizen of the United States, residing at Roselle, in the county of Union and State 5 of New Jersey, have invented certain new and useful Improvements in Lighting Devices for Sewing Machines, of which the following is a specification, reference being had therein to the accompanying drawings.

10 Electric lighting devices for sewing machines, particularly when applied to machines operating at high speed, are subjected to a type of vibration which has a tendency to shorten the life of the lamp-filaments.

15 The vibration of the machine frame is of small amplitude but is sometimes of a severe, sharp, or jarring character, in the nature of a rapid succession of hammer blows. While, by mounting the lighting

20 device adjacent the bend of the sewing machine gooseneck, the destructive effect of this vibration on the lamp-filament is sufficiently reduced to permit the attainment of a satisfactory life by lamp-bulbs having filaments

25 of the more rugged types, such as carbon or the metallized filaments, it is an object of the present invention to further reduce the vibration transmitted to the lamp-filament, or soften its character, in order that a satisfactory life may be attained by lamps having filaments of the more delicate types, such as tungsten filaments.

Another object of the invention is to reduce the vibration of the lamp-filament in a 35 sewing machine lighting device retaining the advantages of the constructions disclosed in the copending applications of Frederick Diehl, No. 449,968, filed March 5, 1921, and Serial No. 453,786, filed March 19, 1921, among which advantages may be mentioned 40 the ease with which the device may be applied to the machine; its effective illumination of the work; its neat and attractive appearance; the absence of objectionable 45 shadows on the work; the freedom from objectionable heat and glare, and the freedom from interference with the dropping of the sewing machine head within the cavity of the usual drop-head cabinet, or with the 50 placing over the machine of the cover of the usual hand-carrying case.

To the attainment of the ends in view, a cushioning device is interposed between the horizontally disposed lamp-socket, which

carries the lamp-bulb and reflector, and the 55 sewing machine gooseneck. The cushioning device should be of compact or condensed form so that the lamp-socket may be sustained closely adjacent the point of connection of the device to the gooseneck. In the 60 embodiment of the invention illustrated, the cushioning device is in the form of a yielding bushing of felt or the like interposed between an inner horizontal sleeve, rigid with the horizontal lamp-socket, and an outer 65 sleeve rigid with a supporting element adapted for connection with the sewing machine frame adjacent the bend of the gooseneck. The cushioning connection being of compact form permits the lamp to be located close to said supporting element and between the standard or vertical member of the gooseneck and the needle-bar head at the free end of the latter, whereby the light 70 may fall obliquely upon the work from a 75 position closely in rear of the middle portion of the overhanging arm, as provided for in said Diehl copending applications. The supporting element may be in the form of a cover-plate adapted to close the usual opening at the rear of a sewing machine gooseneck and having a lateral projection apertured, preferably horizontally, to admit the cushioning sleeve and inner sleeve. The conductor cord may be passed through the 80 apertured supporting element and through the 85 cushioning element to the lamp-socket.

In the accompanying drawings, Fig. 1 is a perspective view of the lighting device as applied to a portable sewing machine. Fig. 90 2 is a horizontal longitudinal section through the cushioning connection. Fig. 3 is a fragmentary side elevation of such connection and Fig. 4 is a plan view of the same.

In the accompanying drawings, a sewing 95 machine head of usual construction is illustrated in Fig. 1 as mounted upon a portable base 1. The sewing machine frame comprises a flat-bed 2 from which rises the hollow gooseneck or bracket-arm including the 100 standard 3 and horizontal member or overhanging arm 3' terminating in the head 4 in which are slidably mounted the usual presser-bar 5 and reciprocating needle-bar 6 carrying, respectively, the presser-foot 7 and 105 needle 8. Cooperating with the presser-foot 7 to feed the work is the usual feed-dog 9. The needle 8 cooperates with the usual loop-

- taker below the bed 2 to form stitches. Machines of this type are usually driven by a suitable motor attachment which has been omitted from the illustration since it forms no part of the present invention. The sewing machine may, of course, be supported and driven in any desired manner.
- The hollow gooseneck or bracket-arm 3, 3' of a sewing machine of the type referred to, is usually provided with an opening 10 affording access to the working parts mounted within the arm. This opening is customarily located at the rearward side of the gooseneck, substantially at the bend of the latter.
- The present lighting device, in the specific form chosen for the purposes of this disclosure, comprises a support in the form of a cover-plate 11 shaped to close the opening 10 and formed with an upper screw-hole to admit the usual cover-plate thumb-screw 12. The cover-plate is formed with a lateral projection preferably in the form of an integral ear 13 bent rearwardly so as to stand in a vertical plane transverse to the plane of the plate 11 proper. The ear 13 is apertured at 14 to admit the reduced end of an outer sleeve 15; said end being spun over at 15' to firmly connect the sleeve 15 to said ear. The other end of the sleeve 15 is cut away to form the diametrically opposed tongues 16.
- Passing through the outer sleeve 15 is the inner sleeve 17 formed at one end with a cylindrical head 18 and shoulder 19; said head being formed with the diametrically opposed flats 20. The other end of the sleeve 17 is threaded to screw into the usual lamp-socket 21. The space between the sleeves 15 and 17 is filled by the cushioning sleeve or bushing 22 of any usual soft, yielding or cushioning material, such as felt. Interposed between the socket 21 and ear 13 is the metal abutment washer 23 and one or more cushioning washers 24 of felt or the like. Also, between the shoulder 19 of the inner sleeve 17 and the adjacent end of the outer sleeve 15 is interposed a cushioning washer 25. This washer is bent over at 26, Fig. 3, against the flats 20 by the tongues 16; the purpose of the opposed tongues and flats being to prevent accidental turning of the lamp-socket 21 and inner sleeve 17 relative to the outer sleeve 15. The bushing 22 and washers 24, 25, are not tightly fitted or clamped in their respective positions and the lighting element is free to partake of a limited yielding rocking movement relative to the support 11.
- The head 18 of the inner sleeve is fitted with an insulating bushing 27 through which sleeve and bushing the conductor cord 28 passes to the lamp-socket.
- The cover-plate 11 may be formed with a lug 29 adapted to externally engage the rim of the aperture 10 and prevent sagging of the lamp and cover-plate. The lamp-socket 21 carries the horizontal lamp-bulb 30 and reflector 31.
- It will be observed that by the means described the lamp is yieldingly supported by a compact cushioning connection with the sewing machine gooseneck adjacent the bend of the latter and is not displaced from its horizontal position closely in rear of and alongside the horizontal arm-member of the gooseneck and between the needle-bar head and the vertical member of the gooseneck. Thus, the advantages flowing from the novel position of the lamp, disclosed in said co-pending applications, are retained and vibration is reduced to the vanishing point by retaining the supporting connection with the sewing machine frame adjacent the bend of the gooseneck and by introducing a cushioning or yielding connection between the lamp-socket and its support. The light from the lamp 30 will thus fall obliquely upon the work from the operator's right and will illuminate that edge of the presser-foot 35 relative to which the edge of the work is customarily guided.
- The described disposition of the light avoids the casting of objectionable shadows upon the work by machine parts carried by or forming a part of the sewing machine bracket-arm. The lamp will not be subjected to the pounding vibration of the sewing machine as the cushioning device interposed between the lamp-socket 21 and the sewing machine frame will absorb or soften the character of such vibration, thus permitting the attainment of a satisfactory life by lamps having filaments of the more delicate types, such as tungsten. The compact form of the cushioning device is such that it is not necessary to space the socket a material distance from the point of support of the device on the sewing machine frame. The favorable position of the lamp in permanent working relation with the bracket-arm and within the vertical planes defined by the side and end edges of the sewing machine bed may thus be retained and the lighting attachment will not interfere with the dropping of the head within the cavity of the usual drop-head cabinet or with the placing of the cover of a hand-carrying case over the sewing head.
- The lighting device may, of course, be applied to sewing machines having frames of any of the usual forms.
- Having thus set forth the nature of the invention, what I claim herein is—
1. A lighting device comprising a support adapted for attachment to a sewing machine gooseneck adjacent the bend of the latter and having an apertured portion, a sleeve entering the aperture in said portion, a lamp-socket and bulb sustained horizontally in the support.

zontally by said sleeve, and a cushioning bushing between said sleeve and said aperture portion.

2. A lighting device comprising a support adapted for attachment to the goose-neck of a sewing machine, an outer sleeve member sustained by said support, an inner sleeve, a lamp-socket carried by said inner sleeve, and a bushing of cushioning material between said sleeves.

3. A lighting device comprising a support adapted for attachment to the goose-neck of a sewing machine, an outer sleeve member sustained by said support, an inner sleeve, a lamp-socket carried by said inner sleeve, a bushing of cushioning material between said sleeves, and cushioning washers at the ends of the outer sleeve.

4. A lighting device comprising a support adapted for attachment to the goose-neck of a sewing machine adjacent the bend of the latter, an outer sleeve member sustained horizontally by said support, an inner sleeve, a lamp-socket carried horizontally by said inner sleeve, cushioning means for yieldingly supporting the inner sleeve within the outer sleeve, and coacting means on said sleeves for preventing rotation of the inner sleeve.

5. A lighting device comprising a support adapted for attachment to the goose-neck of a sewing machine, an outer sleeve member sustained by said support, diametrically opposed tongues at one end of said outer sleeve member, an inner sleeve member formed at one end with a head having diametrically opposed flats coacting with said tongues to prevent rotation of the in-

ner sleeve, a lamp-socket secured to the other end of the inner sleeve, and a cushioning bushing interposed between said sleeves.

6. A lighting attachment for sewing machines comprising, a cover-plate adapted to close the usual opening at the rear of a sewing machine bracket-arm, an electric lamp-socket disposed horizontally and a cushioning connection between said cover-plate and lamp-socket for supporting the latter horizontally in close proximity to said cover-plate.

7. A lighting attachment for sewing machines comprising, a cover-plate adapted to close the usual opening at the rear of a sewing machine bracket-arm, said plate being formed with a lateral ear transverse to the plane of the plate proper, an electric lamp-socket disposed closely adjacent said ear, and a cushioning connection between said ear and lamp-socket for supporting the latter horizontally.

8. A lighting attachment for sewing machines comprising, a cover-plate adapted to close the usual opening at the rear of a sewing machine bracket-arm, said plate being formed with a horizontally apertured projection transverse to the plane of the plate proper, an electric lamp-socket secured to said projection in close proximity to the latter and substantially in line with the aperture in said projection, cushioning means interposed between said socket and said projection, and a conductor-cord passing to said socket through the aperture in said projection.

In testimony whereof, I have signed my name to this specification.

WILLIAM H. BRADY.
